(57) **CLAIM**

The ornamental design for a case for holding a music player, as shown and described.

DESCRIPTION

FIG. 1 is a perspective view of a case for holding a music player showing the new design;

FIG. 2 is a side perspective view shown in use;

FIG. 3 is a front view of a case for holding a music player;

FIG. 4 is a rear view of a case for holding a music player;

FIG. 5 is a top view of a case for holding a music player;

FIG. 6 is a right side view of a case for holding a music player;

FIG. 7 is a left side view of a case for holding a music player;

FIG. 8 is a top view of a case for holding a music player in attachment process;

FIG. 9 is a front view of a case for holding a music player with alternate attachment mechanism. The strap goes through the loop and continues back around to attach the slit to the appropriate button;

FIG. 10 is a front view of a case for holding a music player with alternate attachment mechanism. The strap goes through the loop and continues back around to attach the two ends of the securing clip;

FIG. 11 is a front view of a case for holding a music player with alternate attachment mechanism. The strap goes through the loop and continues back around to attach the loop to the appropriate button.

FIG. 12 is a front view of a case for holding a music player with alternate attachment mechanism. The strap goes through the loop and continues back around to attach the two sides of the snaps; and,

FIG. 13 is a front view of a case for holding a music player with alternate attachment mechanism. The strap goes through the loop and continues back around until the buckle finds the appropriate hole for securing.

The broken lines contained in the Figures are for illustrative purposes only and form no part of the claimed design.
